US00D524438S

(12) **United States Design Patent** (10) **Patent No.:** **US D524,438 S**
(45) **Date of Patent:** **** Jul. 4, 2006**

(54) **PORTION OF A CEILING FAN HOUSING**

(75) Inventors: **Rolando Hidalgo**, Orange, CA (US);
Mark Gajewski, Avila Beach, CA (US)

(73) Assignee: **Minka Lighting, Inc.**, Corona, CA
(US)

(**) Term: **14 Years**

(21) Appl. No.: **29/234,511**

(22) Filed: **Jul. 19, 2005**

(51) **LOC (8) Cl.** **23-04**

(52) **U.S. Cl.** **D23/411**

(58) **Field of Classification Search** D23/377,
D23/379, 385, 411, 413; 392/364; 416/5

See application file for complete search history.

(57) **CLAIM**

The ornamental design for a portion of a ceiling fan housing, as shown and described.

DESCRIPTION

FIG. 1 is a perspective view from below of a portion of a ceiling fan housing in accordance with our design;

FIG. 2 is a top plan view of the portion of a ceiling fan housing in accordance with our design;

FIG. 3 is a bottom plan view of the portion of a ceiling fan housing in accordance with our design;

FIG. 4 is a side elevation view of the portion of a ceiling fan housing in accordance with our design, the opposite side being a mirror image of that shown; and,

FIG. 5 is a front perspective view of the portion of a ceiling fan housing in accordance with our design.

The broken lines showing environmental structure are for illustrative purposes and form no part of the claimed invention.
